J. MERRITT.

HERMETIC SEALING APPARATUS.
APPLICATION FILED MAR. 5, 1906.

1,026,404.

Patented May 14, 1912.

UNITED STATES PATENT OFFICE.

JOSEPH MERRITT, OF HARTFORD, CONNECTICUT, ASSIGNOR, BY MESNE ASSIGNMENTS, OF ONE-HALF TO BEECH-NUT PACKING COMPANY, OF CANAJOHARIE, NEW YORK, A CORPORATION OF NEW YORK, AND ONE-FOURTH TO WILLIAM A. LORENZ AND ONE-FOURTH TO WILLIAM H. HONISSL, BOTH OF HARTFORD, CONNECTICUT.

HERMETIC-SEALING APPARATUS.

1,026,404.

Specification of Letters Patent.

Patented May 14, 1912.

Application filed March 5, 1906. Serial No. 304,399.

To all whom it may concern:

Be it known that I, JOSEPH MERRITT, a citizen of the United States, and resident of Hartford, in the county of Hartford and 5 State of Connecticut, have invented certain new and useful Improvements in Hermetic-Sealing Apparatus, of which the following is a full, clear, and exact specification.

This invention relates to apparatus for 10 hermetically sealing jars of the class in which a more or less complete vacuum is formed within the jar and the cap or cover is retained in place by the outside atmospheric pressure, which presses the cap down 15 upon an elastic gasket inserted between the cap and the jar.

This invention is herein shown in connection with apparatus in which, after a suitable vacuum is obtained within and 20 around the jars, the jar caps are pressed firmly down before and during the readmission of the atmospheric pressure to the jars, thus finally and securely sealing the closures without leaving any chance for the read- 25 mitted air to enter the closure joints, and thus destroy or diminish the vacuum in the jars. In sealing these jars on a commercial scale, it is desirable to operate simultaneously upon a number of jars. In thus oper- 30 ating upon a group of jars, the difficulty is encountered that the tops of the caps are of different heights from the base or tray on which the jars rest, caused by variations incident to the commercial manufacture of 35 the jar, the gasket and the cap. Therefore, if the group of caps were to be pressed down by a single level platform, the pressure would be distributed unevenly on the jars, because of their varying heights. The taller 40 jars, and sometimes only one or two of them, would receive all of the pressure, leaving the shorter jars either without pressure, or with an amount of pressure insufficient to securely close the joint against the read- 45 mission of air. It is moreover desirable to place the group of jars compactly together within a sealing chamber having the smallest possible cubical contents, so as to lessen the amount of air to be exhausted, and conse- 50 quently lessen the time and expense of ob-

taining a proper vacuum. For strength, compactness and moderate cost, it is desirable and customary, to employ for these sealing chambers a horizontal cylindrical shell, in which the jars are placed vertically. 55 In order to enable a cylinder of small diameter to be employed, it is desirable to use for imparting the sealing pressure, operating means disposed and moving lengthwise of the cylinder, or at least at an angle with the 60 vertical position of the jars.

The objects of the present invention are to provide means for translating the direction of movement of the operating bar or bars, and for dividing and distributing the 65 said pressure with substantial equality upon a plurality of the jars, regardless of their varying height.

In the present embodiment of this invention the operating bar from the motor 70 or prime mover is disposed and moves longitudinally of the sealing chamber, its direction of movement being translated and distributed to the respective pressers by means of bell-cranked levers and springs in- 75 tercalated between the prime mover and the pressers. In the commercial sealing of these jars, in which they are handled in great numbers and with great haste, the caps or covers C are liable to become tilted, due to 80 inequalities or irregularities in the joint, either during the capping operation, or when placing them in the sealing retort, or during the pressing down operation itself. Therefore, it is desirable, in connection with 85 the direction translating and pressure equalizing devices of the present invention to provide for leveling the caps which may thus be, or become tilted, and for maintaining them in a level position during the pressing 90 down operation. To this end separately mounted and guided jar pressers are em- 95 ployed in connection with the equalizing springs and direction translating devices, thus dividing these important functions and providing for each function its suitable de- vice.

Figure 1 of the drawings is a side view, in section on the line 1—2 of Fig. 3, of a jar sealing apparatus with the present in- 100

vention incorporated therein and showing the parts in position for exhaustion. Fig. 2 is a similar view and shows the parts in the position occupied by them after the caps have been pushed down at the close of the exhausting operation. Fig. 3 is an end view of Fig. 1 in section on the line 3—3.

The jar chamber 11 is preferably of a cylindrical form inclosed by the shell 12. A door 15 adapted to be closed hermetically gives access to the interior of the chamber. Brackets 14 secured to or resting upon the shell 12 sustain the base 13 upon which rests the jar tray 17 which receives and supports a set of jars J in fixed position during the exhausting and sealing operations. The set of jars consists in the present instance of three rows of nine jars each, making 27 jars in all. The number is, however, immaterial, as the apparatus may be made to operate on any convenient number of jars at once. Connection with suitable exhausting apparatus is made through the pipe 21 and is controlled by the cock 22. A cock 23 is also provided by which communication may be had with the outside air.

Above the base 13 and supported thereon by the uprights 26 is the presser guide plate 25, through which the stems 32 of the jar pressers 31 extend. The pressers 31 are so disposed that each one overlies a jar J when the tray 17 is properly located on the base 13. Each presser stem 32 is loosely pivoted at 33 to a crank lever 34 fulcrumed at 35 in lugs 36 appurtenant to the plate 25. The upper end of each lever 34 is forked (Fig. 3) to straddle the sliding collar 39 with which it is connected by pins 40 which fit into a groove in the collar. The collars 39 are mounted to slide on the operating bar 45 which is supported for endwise movement in brackets 46 (Fig. 1) secured to the top of the plate 25. The rear end of the bar 45 passes through a stuffing box 47 to the exterior of the jar chamber where it is connected to a motor or other suitable source of power and operates as a prime mover for the entire apparatus. The operating bar 45 also carries a series of fixed collars or abutments 41 secured to the bar at intervals along its length adjacent to and corresponding in number with the sliding collars 39. Between each fixed collar 41 and the sliding collar 39 next it toward the rear, is a spring 42, which is under some tension and therefore crowds its sliding collar 39 against the fixed collar 41 at its rear. When it is desirable to operate a plurality of rows of pressers with the same prime mover, as herein shown, additional sliding bars 50 also equipped with springs and collars extend over the two outer rows of jars and are moved by the operating bar 45 by means of the two yokes 48 and 49 which are secured to the bars at either end or at convenient

intervals. The yoke 48 is utilized in the present instance to sustain the thrust of the spring 42 at the front end of the bar 45.

The operation of the apparatus is as follows:—The tray 17 with its complement of jars J ready for sealing is placed within the jar chamber 11 in such position that the jar caps C are all beneath their respective pressers. The door 15 is now closed, the cock 23 closed, and the cock 22 opened, all the parts being now in the position shown in Fig. 1. This enables the jar chamber 11 to be exhausted until the desired degree of vacuum has been reached, the caps C being free to lift sufficiently to permit the air to also pass out from the interior of the jars. The operating rod 45 is now moved endwise by the motor mechanism to the position shown in Fig. 2. This swings the crank levers 34 on their pivots 35 and moves all the pressers 31 downward until they encounter their respective caps C. Each cap will then be forced by its presser down upon its jar as the fixed collars 41 will continue to crowd the springs 42 against the sliding collars 39 until the bar 45 completes its movement. The springs serve as equalizing members, to distribute the pressure with approximate equality upon all of the caps. By suitably proportioning the springs, and adjusting the stroke so as to bear with sufficient pressure upon the lowest caps, the differences in pressure, due to the differences in amount of compression of the springs, need not be considered. The cock 22 may now be closed and the cock 23 opened thereby readmitting the air to the jar chamber 11 so as to reestablish atmospheric pressure therein. No air can enter the closure joints of the jars during this operation as the caps are all held down firmly by the pressers. The latter may now be released by sliding the operating bar forward and the caps will be retained in place by the atmospheric pressure.

In the drawings the jars are shown to be of different heights. Those pressers which stand on the high jars will be the first to be arrested in their downward movement, the next highest stopping next, and so on until all the caps are pressed down into place.

It is preferable to arrange the springs and collars so that the springs are compressed to some extent even when the pressers are in their upper position. By properly regulating this tension each presser will exert the desired minimum pressure upon its cap as soon as its movement is arrested by the cap without any movement being lost in the initial compression of the spring.

The action of the springs 42 in distributing and substantially equalizing the pressure transmitted from the prime mover or operating member to the pressers may be understood by comparing them with what

would be the case if the springs were removed, and if the collars 41 were to bear directly against the levers 34, without the interposition of the springs. Obviously, in that case, the entire pressure would be concentrated upon the highest jar or jars, so that the pressers would not reach the lower jars at all; but the springs when interposed between the collars 41 and the levers 34, as 10 in the present invention, permit the continued movement of the prime mover until its pressure is distributed and substantially equalized upon all the jar caps, as is illustrated in Fig. 2 of the drawings, in which 15 the jars are shown to be of varying heights in order to illustrate this feature. In that arrangement, the difference in pressure upon the different jars is comparatively slight, lacking of perfect equalization only to the 20 extent due to the difference in tension of the different springs, due to their differing amount of compression, which is or may be made very slight, depending upon the initial compression of the spring, which need not 25 be great. The amplitude of movement of the prime mover or operating bar 45, and the power applied to it being made sufficient for the purpose, the pressure upon the lowest jar may be made sufficient for the intended purpose; and the slight excess of 30 pressure which may be put upon the other jars, due to the slightly varying movements of compression of the respective springs, does no harm, so that the springs are herein 35 properly designated "equalizing springs", since they substantially equalize the pressure distributed from the operating bar 45 to the respective pressers.

I claim as my invention:—

40 1. In jar sealing apparatus, a plurality of individual jar pressers, an operating member, devices for translating the direction of pressure from the operating member to the jar pressers, and springs for distributing and substantially equalizing the pressure transmitted to the said individual pressers.

2. In jar sealing apparatus, a plurality of individual jar pressers, an operating member common to the plurality of pressers, a 50 direction translating device interposed between the said operating member and each of its individual pressers, and springs for distributing and substantially equalizing the pressure transmitted to the said pressers.

55 3. In jar sealing apparatus, a plurality of individual jar pressers, means for guiding the movement of the pressers, an operating member movable at an angle with the movement of the pressers, direction translating devices interposed between the operating member and the individual pressers, and an equalizing spring interposed between each presser and its operating member, for distributing and substantially equalizing the pressure transmitted to the pressers.

4. In jar sealing apparatus, the combination of a jar chamber, a series of independently movable jar pressers, means for guiding the movement of the pressers, an operating member for the said series of pressers, 70 movable in a direction at an angle with the movement of the pressers, direction translating devices interposed between the said operating member and its individual pressers, and equalizing springs between the operating member and the respective pressers for distributing and substantially equalizing the pressure transmitted to the said pressers.

5. In jar sealing apparatus, the combination of a jar chamber, a set of independently movable individual jar-pressers, means for guiding the pressers, an operating bar, a set of equalizing springs carried on the bar, and connecting means for transmitting the substantially equalized movement of the springs 85 to the pressers.

6. In jar sealing apparatus, the combination of a jar chamber, a set of independently-movable individual jar pressers, an 90 endwise-movable operating bar, a set of equalizing springs carried on the bar, a series of abutments secured to the bar and separating the springs, and a set of levers connecting the springs and the pressers, 95 whereby the endwise movement of the bar is transmitted through the springs to the pressers.

7. In a jar sealing apparatus, the combination of a jar chamber, a presser guide 100 plate secured therein, a set of independently-movable individual jar pressers carried by the plate, an endwise-movable operating bar, a set of springs carried on the bar, a set of abutments secured to the 105 bar and separating the springs, and a set of levers pivoted on the guide plate and connecting the springs and the pressers, whereby the endwise movement of the bar is transmitted through the springs to the pressers. 110

8. In jar sealing apparatus, the combination of a jar chamber, a plurality of independently movable individual jar pressers, means for guiding the movement of each presser, an operating bar and connecting 115 means between the said bar and the plurality of pressers, including springs for transmitting substantially equalized pressure from the bar to the pressers.

9. In jar sealing apparatus, the combination of a jar chamber, a set of independently movable jar pressers, means for guiding the movement of said pressers, an operating bar and connecting means including springs between the bar and the pressers, for dividing 120 and distributing pressure from the bar to the pressers. 125

10. In jar sealing apparatus, the combination of a jar chamber, independently movable jar pressers, a plurality of operating 130

bars for the said pressers, and connecting means including springs between the said bars and the respective pressers for dividing and distributing the operating pressure from the said bars to the respective pressers.

5 11. In jar sealing apparatus, the combination of a jar chamber, independently movable jar pressers, a plurality of operating bars, a yoke connecting the said bars and 10 connecting devices including springs for dis-

tributing substantially equalized pressure from the said bars to the respective pressers.

In witness whereof I have signed my name to this specification, in the presence of two subscribing witnesses, this 3d day of March, 1906.

JOSEPH MERRITT.
